DESIGN FOR A STUFFED DOLL OR SIMILAR ARTICLE

Leo L. Weiss, New York, N. Y.

Application August 22, 1941, Serial No. 102,984

Term of patent 7 years

To all whom it may concern:

Be it known that I, Leo L. Weiss, a citizen of the United States residing at New York city, in the county of New York and State of New York, have invented a new, original, and ornamental Design for a Stuffed Doll or Similar Article, of which the following is a specification, reference being had to the accompanying drawing, forming part thereof.

In the drawings:

Fig. 1 is a front perspective view of a stuffed doll showing my new design;

Fig. 2 is a rear view thereof, in perspective, and

Fig. 3 is a rear view of the doll with the limbs extended.

I claim:

The ornamental design for a stuffed doll or similar article, substantially as shown and described.

LEO L. WEISS.
